UNITED STATES PATENT OFFICE

2,076,472

BUILDING CONSTRUCTION

Bernard London, New York, N. Y.

Application February 28, 1936, Serial No. 65,771

53 Claims. (Cl. 72—16)

This invention relates to building construction. This application is a continuation in part of my application Serial No. 23,669, entitled "Building Construction", filed May 25, 1935.

5 One of the objects of this invention is to provide a practical and inexpensive building construction and to facilitate and expedite speedy and inexpensive fabrication of building units or parts, the assembly thereof in practice, and the construction of a building in general. Another object is to provide practical and durable means of assembling, either in course of fabrication as in a factory or in the course of construction work or erection in the field, component parts of my 10 building construction.

Another object is to provide a strong, dependable, efficient, and yet inexpensive, building-wall construction utilizing concrete and also to achieve such a construction in such a way as to facilitate, 15 efficiently and inexpensively, the incorporation therein, if desired, of heat insulating materials or constructions.

Another object is to provide a building construction embodying therein concrete with a reinforcement that is inexpensive, practical, durable, of light weight, strong, and capable of being quickly and inexpensively embodied into the structure. Another object is to provide a concrete partition or wall structure capable of rapid 20 and inexpensive construction in the field and in which may be embodied, if desired, any of a wide range of sheet materials for either interior or exterior surface finish thereof, or both, and in which may be embodied dependable and efficient heat insulation means.

Another object is to provide a strong, efficient, light and inexpensive means for spacing and holding apart sheet materials to form portions of a building, or the like, and where and if desired 25 to form with concrete poured in between the spaced sheet material a strong, light, and durable, yet inexpensive, reinforcement for the concrete. Another object is to provide a building construction of the above-mentioned character 30 which will lend itself to wider variety or diversification of installation or interrelation as, for example, with certain other types of material of building construction or of wall surfacing and thus to provide a greater and wider range of 35 flexibility of use or application of certain building units of my invention. Other objects will be in part obvious or in part pointed out hereinafter.

The invention accordingly consists in the features of construction, combinations of elements, 40 and arrangements of parts as will be exemplified

in the structure to be hereinafter described and the scope of the application of which will be indicated in the following claims.

In the accompanying drawings, in which are shown certain of various possible embodiments 5 of my invention, all by way of illustration,

Figure 1 is a horizontal sectional view on an enlarged scale through a wall such as an outside wall showing certain features of my invention as carried out when it is desired to embody, in constructing the building, means such as poured concrete;

Figure 2 is a perspective view on an enlarged scale of a spacing and reinforcing element employed in the construction of Figure 1;

Figure 3 is a vertical sectional view through an outside wall showing certain features of construction of the latter and of a preferred method of assembly thereof in actual practice;

Figure 4 is a perspective view on an enlarged scale of another form of spacing and reinforcing element;

Figure 5 is a top plan view of a building unit embodying sheet metal outer elements with appropriate spacing means;

Figure 6 is a similar view showing another mode of assembly thereof;

Figure 32 is a vertical sectional view as seen along the line 32—32 of Figure 30;

Figure 33 is a horizontal sectional view of a wall construction showing a possible mode of construction for assembling sheet members to spacer members;

Figure 34 is a vertical sectional view thereof as seen along the line 34—34 of Figure 33;

Figure 35 is a view like that of Figure 34 showing a modified form of construction;

Figure 36 is a view like Figure 3 showing the manner in which certain features of my invention may be assembled for reception of poured concrete;

Figure 37 is a vertical sectional view showing a flooring and ceiling construction;

Figure 38 is a vertical sectional view showing the relation of the floor and ceiling construction of Figure 37 to a wall;

Figure 39 is a plan view as seen from the top of Figure 36 but showing also how the construction may be carried around a corner;

Figure 40 is a side elevation partly in section, for example as seen along the line 40—40 of Figure 36, showing certain details of the construction and also means for spacing the reinforcing spacer members;

Figure 41 is a sectional view on an enlarged scale as seen along the line 41—41 of Figure 40;

Figures 42 and 43 are, respectively, vertical sectional views, on an enlarged scale, like that of Figure 41, showing possible modified forms of transverse spacer members for the reinforcing spacers;

Figure 44 is a top plan view of a building unit construction;

Figure 45 is a view of a modified form of building unit construction as seen from the top thereof, for example;

Figure 46 is a vertical sectional view as seen along the line 46—46 of Figure 45;

Figure 47 is a sectional view like that of Figure 46 showing a modified form of construction;

Figure 48 is a transverse sectional view of a sheet material out of which certain parts of my construction may be made;

Figure 49 is a front elevation showing an adaptation of parts of the structure of Figure 48;

Figures 50 and 51 are sectional views of possible forms of corner constructions;

Figure 52 is a horizontal sectional view showing certain features of the construction where two walls meet at an angle and showing a form of corner construction, and

Figure 53 is a perspective view on an enlarged scale of a form of spacing and reinforcing element employed in the corner structure of Figure 2.

Similar reference characters refer to similar parts throughout the several views in the drawings.

Referring now first to Figure 1, I have there shown in horizontal section a wall construction having a portion 60 thereof constructed like the building units disclosed in my application Serial No. 752,969, filed November 14, 1934, now Patent No. 2,039,601 or as is described in my co-pending application Serial No. 23,369, filed May 25, 1935, or embodying structural features later described herein and shown more particularly in Figures 45, 46 and 47. The portion 60 comprises inner and outer sheet members 61 and 62 made, as described in my above-mentioned applications, of any suitable material and they may, for example, be cast or formed of materials like cement, materials such as are used in tiles and including glaze, any other appropriate material capable of fabrication into the sizes and shapes desired, such as asbestos composition, fiberboard, so-called sheet rock, plasterboard, maze-wood, cardboard, sheet metal, or the like, or they may be cut or sheet stone, marble, or the like; they are preferably dimensioned as to length and breadth to give any desired size of ultimate building unit, the dimensions illustratively being like those set forth in my above-mentioned applications.

Interposed between the spaced slab-like members 61 and 62 is a cellular construction generally indicated at 63 and as illustrated in Figure 1 it is of a construction such as is fully described and shown in my application Serial No. 23,369, though, as indicated above, it may take the form of the cellular structure of my application Serial No. 752,969, or the form later described herein, or, so far as certain other features of my invention are concerned, it may take any suitable or desired form. The parts 61, 63 and 62 are secured together as described in my aforesaid application and achieve advantages of structure and action as therein fully described; it might be noted that among the latter advantages are inexpensiveness of construction, lightness of weight, speed of assembly, heat insulation, soundproofness, fire resistance, and the like.

To the outer member 62 there is secured in any suitable manner or integrally formed therewith a suitable number of vertically extending and preferably closely spaced dovetail members, two of which are shown in Figure 1 at 64 and 65. The spacing may be on the order of one foot or two.

I then provide for each building unit 60 a sheet member 66 of preferably substantially the same area as the member 62 thereof; sheet member 66 may be of any of the materials above-mentioned

and where it is an outside member it is preferably of any suitable material that is well adapted to withstand weather or the like, such as sheet metal, tile, marble, glass, ceramics, composition board, etc., and it has secured to it or integrally formed therewith a suitable number of vertically extending dovetail members 67 and 68 spaced to correspond with the spacing of the dovetail members 64 and 65 etc. of the building unit 60.

10 I then provide spacers illustratively taking the form as is better shown at 69 in Figure 2. The spacer 69 is preferably made of sheet metal thus lending itself to speedy and inexpensive fabrication and it has other features giving it substantial 15 strength and rigidity.

For example, it has a central strip-like portion 70 which is stamped or formed as at 71 preferably along its median or center line to bulge out of the plane of the central portion 70, thereby giving 20 the lengthwise extending portion 70-71 adequate strength and resistance to bending.

At appropriate intervals along its length the member 69 is cut or slit transversely and the resultant pairs of members are bent alternately in 25 opposite directions out of the plane of the portion 70; thereby are formed pairs 72-73 of arms directed to the right as seen in Figure 2 and spaced vertically therefrom are pairs of arms 74-75 extending to the left of the plane of portion 30 70, etc. These various arms are, furthermore, bent again as shown to provide extreme end portions 76 inclined to each other and spaced apart to substantially mate with the angles and spacing of the inclined vertical faces of the dovetails 64-65 etc. of the building units 60 and dovetails 67-68, etc. of the outer sheet members 66.

The sheet members 61 and 62 and the cellular material 63 are shaped, at the edges of the building units, to interfit, as shown clearly at the left portion of Figure 1, the cellular portion 63 of adjacent units being repeatedly reentrant so as to interlock or interfit.

Accordingly, having assembled a suitable number of building units 60 in, for example, the manner described in my above-mentioned applications, I then assemble to the exterior thereof a corresponding number of sheet members 66 (Figure 1) utilizing spacer members 69 to interengage 45 with the respective dovetails, resulting in the relation better shown in Figure 1 and thereby mechanically and securely holding the member or members 66 parallel and in accurate alignment with each other and with respect to the inter-50 fitted wall units 60.

55 Into the space thus provided between the wall units and the sheet members 66 I now pour concrete or other appropriate plastic material indicated at 77 in Figure 1. Material 77 is of a thickness commensurate with the spacing between the wall units and the sheet members 66 and that, of course, may be made whatever it is desired by correspondingly constructing the spacers 69. The poured concrete bonds itself to the wall units 60 and also to the sheet members 66 and, furthermore, interlocks with the various dovetails on both the outside sheet members 66 and on the building units 60 for, it will be noted, the alternate arrangement of the pairs of gripping arms 65 of the spacer 69 (Figure 2) insures a free flow of the concrete into interlocking interengagement with the thereby exposed portions of the various dovetails.

70 By suitably selecting the material of which the 75 external sheet members 66 are made, as already

illustratively set forth above, the external face of the wall is neat and smooth and requires no patching up or surface finishing, as is the case with present-day methods of pouring concrete structures, where the forms are subsequently removed and the impressions left by the forms, usually of timber, in the exposed surfaces of the concrete have to be gone over or otherwise surfaced or finished. Furthermore, unless specially treated concrete is soft and porous but with my invention and by appropriately selecting the materials of the external sheet members, the latter make the wall structure externally waterproof and water-resistant, and capable of withstanding rough wear and also the elements.

10 The resultant construction is one that embodies numerous of the advantages of concrete, the latter, it being noted, being well reinforced by the spacer and reinforcing members 69, the latter having also the effect of increasing the 15 load-carrying capacity of the resultant structure. The external wall finish has been just mentioned above and as for the remainder of the wall, as made up by the building units 60, the latter give thereto such important advantages as those noted 20 above, not the least of which is desirable heat insulation. Furthermore, the inside sheet members 61 of the building units 60 may be selected of a material such as is appropriate for inside wall 25 finishes and thus the resultant wall structure gives the inside of the building or enclosure the desired character of wall surfacing, thereby making it possible to eliminate plastering and the like.

30 As earlier above mentioned the building units 60 may take other forms. For example, where it is not important fully to achieve the advantages of the sealed or cellular construction 63, the building units 60 may take the form shown in Figure 44 in which the outer and inner sheet members 62 and 61 have interposed therebetween a repeatedly and alternately reentrant, illustratively, corrugated, sheet member 78 whose waves, curvatures, alternations or corrugations are of a depth commensurate with the spacing that is desired to be maintained between the outer and inner sheet 35 members 62, 61. Sheet member 78 is fabricated of any suitable material, for example, such of the materials earlier mentioned as lend themselves to such fabrication. The three parts 61, 78 and 62 are secured together in any suitable manner, preferably along the lines of tangency thereof, as by metallic tie members, nails, staples, screws, rivets, wire, or the like, as indicated at 89, and a preferred manner of securing them together is by way of a preferably water-insoluble cement 79 40 applied where and as shown in Figure 44, thereby to coat with the respective sheet members throughout substantial areas. The cement employed may be such as those mentioned in my 45 above-mentioned applications.

50 Another form which the building units 60 may take is shown in Figures 45 and 46 in which another mode of achieving a sealed air cell or cellular structure is shown. Here are shown the inner and outer sheet members 62 having interposed between them two corrugated sheet members 80 and 81 spaced from one another, members 80 and 81 being otherwise like the member 78 of Figure 44, with, however, smaller corrugations.

55 The crests of member 81 are slotted as at 81^a and in the same plane the troughs of member 80 are slotted as at 80^a (see also Figure 46). Into these slots 80^a-81^a, all aligned and in the same plane, is received a strip-like sheet member 82 (Figures 45 and 46) shaped as is better shown in 60

75

the right-hand portion of Figure 45, being bounded by the two full lines 82^a and 82^b, each being made up of straight line and curved line portions. The straight line portions are the ones 5 that are received in the slots and the curved line portions thereof are shaped to be seated into the corresponding troughs of the waved or corrugated members 80—81. A suitable number of members 82 are interposed between the corrugated members 80—81 in a direction transversely to the 10 axes of the corrugations thereof, and in Figure 46 three such members 82 are shown; they thus act to space the members 80—81 and also to sub-divide the space therebetween into chambers.

15 The members 80—81, however, are also slotted intermediate of the slots 80^a and 81^a; thus, the crests of member 80 are slotted as at 80^b (see also Figure 46) and preferably in the same plane the troughs of member 81 are slotted as at 81^b to receive strip-like sheet members 83 and 84, respectively, member 83 having a straight edge 83^a that seats against the sheet member 62 and having a juxtaposed edge shaped as is better shown in the right-hand portion of Figure 45 by the broken and full line 83^a, while member 84 is similarly shaped, both having curved portions that seat into certain of the troughs of the respective corrugated members and having straight portions that fit into and extend through the slots 80^b and 81^b, respectively. Members 83 and 84 thus sub-divide the spaces between their respective corrugated members and the facing members of the building unit into a large number of relatively small but closed chambers, cells, or air pockets.

35 The various parts are held in assembled relation by any suitable cement, thereby also sealing the various cells and chambers. When made of a suitable heat non-conducting material, heat transmission through the resultant wall structure or building unit, by conduction, is effectively minimized or negated by reason of the long paths of flow which the heat must take in passing from one sheet member 62 to the other sheet member 61 or vice versa (see Figure 46), each possible path of flow being very materially greater than the shortest straight line distance between the two sheet members. Other advantages in heat insulation are some of those mentioned in my above-mentioned applications.

50 The construction of Figures 45-46 also lends itself readily to the use of sheet metal, as is indicated in Figure 47, which is a fragmentary sectional view like that of Figure 46; here the members, which in Figure 46 are the members 82, take
55 the form of sheet metal members 85 which are provided with prongs or ears 86-87 which are oppositely bent over after passage through the slots 80^a (or 81^a as the case may be) and thus the members 85 facilitate assembly and the securing
60 together of the various parts. In like manner the members 83 and 84 of Figure 46 may be made of sheet metal and similarly provided with bendable ears that are bent over after passage through the slots in the corrugated members. Though
65 metallic parts are employed in the modification of Figure 47, it will be noted that any path of heat flow that includes such members includes, however, a substantial length of path through the insulating or heat non-conducting material of the
70 corrugated members 80 and 81, and thus it is still possible to achieve satisfactory heat insulation.

The building units or wall portion 60 of Figure 1 may, it will thus be seen, also take other forms, illustratively those of Figures 44-47, and it is with such constructions as these that I may

interrelate poured concrete with reinforcing spacers and with exterior sheeting, as was described in connection with Figures 1 and 2 but which may take certain other forms according to other features of my invention.

For example, instead of utilizing a plurality of spacer members 69, as shown in Figures 1 and 2, I may employ a unitary reinforcing spacer construction, such as is shown in perspective in Figure 4, wherein a portion of one of these members, generally indicated by the reference character 90, clearly appears as to its structural features. 10

Member 90 is made of sheet metal of any suitable or appropriate gage or thickness or character and because of certain features of its construction a relatively light gage of sheet metal may be employed. Its construction is such as lends itself to ready manufacture, as by way of a suitable press operating, for example, in successive steps or stages to give the initially plane sheet metal the desired features of shape and construction. It is shaped to have a number of vertically extending column portions, of which 4 are shown, at 91, 92, 93 and 94, in Figure 4 by way of illustration, each comprising a rib R pressed out of the plane of the plane face portions F, being in general similar to the parts 10—71 of Figure 2 already described.

18—71 of Figure 2 already described. The sheet metal intervening these vertical column portions 91, 92, etc., is slit or cut horizontally to form a considerable number of strap-like horizontal connecting portions which are pressed or bent alternately out of the plane of the column members 91, 92, etc. Thus, in Figure 4, there is an upper row of strap-like connectors 95, 96 and 97, shaped to have inclined wings W¹ and W² joined at their outer and inner ends by a cross-piece C, the latter having preferably a rib R¹ pressed therein. 30 35 40

The next row of strap-like connector portions has the latter extending to the opposite side of the plane of the column portions 91, 92, etc., and the illustrative three connector portions appear in Figure 4 at 98, 99 and 100, each comprising 43 portions W¹, C, R¹ and W², as above described.

The next horizontal row comprises the connector parts 101, 102, 103 extending to the same side of the plane of the column parts as do the connector parts 95, 96, 97, the next horizontal row comprises the connector parts 104, 105, 106 extending to the same side of the central plane as do the parts 98, 99, 100, and so on, it being noted that the parts W¹, C, R¹ and W² of all of the connector parts that extend in vertical rows are respectively aligned; these parts 98, 104, etc., parts 95, 101, etc. form two vertical rows, one to each side of the central plane, and so on.

to each side of the central plane, and so on. At its vertical ends the member 90 terminates preferably in such a way as to interfit with another member 90 that may be aligned with it edge to edge to form a continuation. The members 90 may be made of any suitable size or dimension; illustratively, the spacing center to center of the column portions 91, 92, 93, etc. may be on the order of five inches or so, the vertical dimension or width of the connecting strap-like members, such as member 95 or 98 or 105 may be on the order of two inches, and hence the spacing between the horizontal rows is of a like order. Each one of these connecting strap-like members may protrude from the central plane by a distance on the order of two inches, making the thickness of the member 90 on the order 60 65 70 75

of four inches. Member 90 may be of any desired vertical and horizontal dimensions depending upon the specific character of application thereof and within the range of feasible or commercial construction out of plain sheet metal; illustratively each member 90 may be several feet in height and several feet in width; if desired, they may be made of dimensions commensurate with those of the individual building units 10 61, as to length and breadth.

Also, and if desired, the members 90 may be made without the ribs R¹ of Figure 4 and in Figure 5 such a construction of the member 90 is shown, the portion C being devoid of the rib R¹. 15 In either case I employ the member 90 to make up a building unit preferably for the reception of concrete and in Figure 5 such a unit is shown comprising the member 90 with sheet members 110 and 111, each on one side of the member 90 20 and resting flatwise against the faces C of the latter, to which they are respectively secured in any suitable manner. Where the members 110, 111 are made of sheet metal, this securing may be effected as by welding, as is indicated in Figure 5 at 112; or I may employ rivets 113 (Figure 25 6) where the sheet members 110 and 111 are of a material to permit their use, such as sheet metal, fiberboard, and like relatively tenacious composition sheets or other appropriate material. Where I employ rivets, the latter may be arranged in any desired geometrical, decorative or other ornamental or attractive scheme or arrangement as may be permitted by the availability of faces C of the interposed spacer and 30 reinforcing member 90.

Where the construction is thus made unitary, as in Figures 5 and 6, the three-part construction may be prefabricated in suitable units of appropriate size and shipped for installation and 40 use on the job in a manner more fully described later.

Of the wide variety of commercially available non-metallic sheet materials, of which a number are illustratively mentioned above, I may and 45 preferably do employ other means for securing such sheet members to the respective sides of the spacer and reinforcing member 90. Illustratively, the faces C of the member 90, turning now to Figure 7, are preferably plane and there are struck up two alined tongues 114 and 115 (see also Figure 8), extending vertically, but bent away from each other at their outer ends, thus in plan view (Figure 7) to give the general effect of the shape of the letter T. The member 90 thus appears with vertical rows of alined T-shaped projections 114-115, the rows being horizontally spaced.

Now the sheet members to be related to the member 90, shown in Figure 7 at 116 and 117, 50 are provided with slots or grooves 118 correspondingly spaced horizontally and preferably T-shaped in cross-section, as is better shown in Figures 16 and 17, slots 118 being preferably of slightly lesser dimension than the T-shaped tongues 114-115.

Accordingly, the sheets 116-117 (Figures 7 and 8) may be secured to the reinforcing and spacer member 90 by sliding one relative to the other so that the alined tongues 114-115 snugly and 55 tightly enter the T-shaped slots 118, the assembly resulting in what is shown in Figure 7.

Under some circumstances, it may be desirable to arrange these parts for interrelation by sliding them together horizontally rather than vertically, 70 and in such case the T-shaped tongues 114-115

extend horizontally of the faces C rather than vertically, as in Figures 7 and 8, and in Figure 9 this horizontal relation is shown, the horizontally extending T-forming prongs or tongues being shown at 114^a and 115^a. In such case the slots 118 in the sheet material extend horizontally or if the spacing is appropriate the sheet members of Figure 7 are simply turned through 90° and then interrelated with the T-forming tongues. 10

Where desired, the sheet material may be given T-shaped slots or grooves extending in both horizontal and vertical directions, as is indicated in Figure 18 in which a sheet member 116^a appears with vertical T-shaped slots 118^a and horizontal T-shaped slots 118^b intersecting them; though in Figure 18 the spacings are the same so as to form a series of squares it is to be understood that the spacings between the vertical slots and the spacings between the horizontal slots need not be the same but may be different to meet the requirements of constructions of the spacer members 90 in which the T-forming prongs or parts might be arranged in rows of different spacings; for example, the vertical rows of Figures 7 and 8 may be spaced differently from the spacing of the horizontal rows of T-forming members of Figure 9. In such case, the sheet member 116^a of Figure 18 serves both contingencies. 15 20 25

Thus, the three-part structure, like that of Figure 7, may, if desired, be prefabricated or may be assembled on the field or on the job. However, to facilitate such assembly and to avoid having to slide the several parts, in course of assembly, relative to one another throughout their entire length 30 or lengths, a matter which might on the field entail some disadvantages, I may employ other structural interrelations, illustratively that shown in Figures 13, 14 and 15. Turning first to Figure 13, the spacer member 90 is again shown but 35 with the plane parts C thereof provided with a rib R² which, instead of being arcuate, as shown in Figure 4, is angular, as shown in Figure 13; in its two faces the rib R² is provided with substantially rectangular holes 120 and 121 (Figure 14), 40 45 in order to permit the insertion therethrough of hook-shaped tongues 122 and 123, respectively, of a central V-shaped rib R³ that mates with the rib R² of a sheet metal member 124 suitably and rigidly secured to the sheet member 117. 50

Member 124 extends throughout the length of the sheet member 117, there being a number of them secured thereto and parallel to each other, being spaced (Figure 13) to correspond with the spacing center to center of the vertically alined parts or rows C of the member 90. The members 124 may be secured to the sheet material 117 by oppositely bent prongs or tongues 124^a and 124^b interlocked with the slots 118, the latter being preferably T-shaped, as above noted, and in each case and preferably the oppositely directed tongues, when they enter the slots, act like saw teeth to undercut the side walls of the slots and thus securely interengage the sheet material. 55 60

The other sheet member 116 (Figure 13) is 65 similarly provided with members 124. Accordingly, having initially erected the member 90 in vertical position, the sheet members 116 and 117, with their spaced members 124 provided with the hook-shaped tongues 122-123, may be quickly 70 and speedily assembled to the member 90 (see Figures 14 and 15) by causing all of the hook-shaped tongues 122-123 to pass through the holes 120 and 121, respectively, in the parts C and then by moving the sheet member down- 75

wardly, these hook-shaped parts are made to take in back of the parts C and to assume the relationships shown better in Figures 14 and 15. As will later appear, this mode of assembly of 5 the parts has distinct advantages where assembly is carried on in the field.

In like manner and substantially to avoid having to slide the sheet member or members throughout the complete length relative to the 10 spacer members where they take the form of the members 89 of Figures 1 and 2 as above described, I may adopt the structural features shown in Figures 30 and 32. Referring first to Figure 30, there is there shown a single spacer member of 15 a construction generally similar to that shown in Figure 2; it has the same central plane portion 70 reinforced by the rib 71, as in Figure 2, and projecting therefrom are the arms 72-73 in one level and arms 74, 75 in a different level, 20 the pairs of arms alternating as was the case with those of Figure 2.

The ends of these arms, however, are each provided with oppositely bent prongs or tongues 125^a and 125^b (Figure 30), similar to the tongues 25 124^a and 124^b above described in connection with Figure 13 and like the latter they are adapted to interengage with the sheet material in suitable slots in the latter.

This sheet material shown in Figure 30 at 126 30 and 127, is, however, provided with slots or grooves cut or molded therein in any suitable manner, the slots being parallel and appropriately spaced and each having a shape such as is better shown in Figure 32 in which a single 35 slot 127 appears in elevation and is shown to comprise alternate portions 127^a and 127^b of the same depth but of different widths; thus, slot portions 127^a are narrow, being somewhat less in width than the width of the pronged ends 40 125^a-125^b, as viewed in Figure 30, while the slot portions 127^b are of slightly greater width than these pronged portions.

Furthermore, these slot portions are of substantially the same length as the dimension of 45 the arms 72, 73, 74, 75 in the direction of the central ribbed portion 70 thereof.

Accordingly, in assembling the sheet sections 126 and 127 with respect to the spacer construction, the pronged ends of the arms are simply 50 seated into the wider slot portions 127^b, into which they are easily received, whereupon the sheet or sheets and the sheet metal spacer member are given a relative movement in the direction of the length of the slots 127, thereby forcing the prongs 55 or tongues 125^a-125^b into the material of the sheets, causing them to undercut their way into the substance of the sheet material, this relative movement proceeding throughout a distance equal to the length of a slot portion 127^a. The 60 prongs or tongues act like saw teeth and cut themselves a path so as to form ultimately with the slot portions 127^a what is virtually a T-slot, but it will be noted that the relative movement necessary to achieve assembly is but a very small 65 one. Thus, assembly is greatly facilitated either in course of fabrication or in the field. Figure 32 being a section along the line 32-32 of Figure 30, the above described interrelations of the parts are shown in full lines and in broken lines.

70 In Figures 30 and 31 I have shown also how I may make the sheet metal spacer and reinforcing member of lighter sheet metal and still achieve substantial strength or how I may strengthen the spacer constructions already above described. 75 Thus, I may stamp or emboss ribs 128 (Figures

30 and 31) in each of the arms, thereby giving them greater strength and rigidity.

Furthermore, the central rib portion 70 may be strengthened and reinforced by a sheet metal member 129 shaped to interfit with it along its 5 length, as shown in Figures 30 and 31, being similarly arcuate where ribbed lengthwise, and to quickly and dependably secure them together I may spot weld them or I may provide in the part 10 70 suitable holes 130 (Figures 30 and 31) and 10 press or stamp out of the member 129 tongues 131 shaped with respect to the apertures 130 to be easily received therethrough and to take in back of the rib parts 70.

Of course, with all of the above described 15 arrangements of assembling the sheet material to the reinforcing and spacer construction or metal core, the subsequent pouring of the concrete, as is preferred procedure, into the spaces between 20 the sheet members and the spacer construction 25 insures a final and solid securing together of the entire construction, for thereby the cement or concrete becomes bonded to the spaced sheet members and securely holds them together, the spacer construction reinforcing the concrete and permitting the thickness of the concrete layer to be made much less than would otherwise be the case.

In Figures 33 and 34 I have shown another 30 mode of interrelating the reinforcing spacer means and the sheet members and illustratively the spacer construction preferably takes the form of that shown in Figure 4 and above described in full. The sheet members 141 and 142 have secured to them corrugated strips 143 and 144, 35 respectively, these strips being made of any suitable material, such as those of the materials above mentioned for the composition of the sheet members themselves as lend themselves to a configuration such as that of the strips of Figure 33. 40

For example, these strips may be sawed or cut 45 out of a large sheet of corrugated composition board, the width of the strips being equal to or slightly less than the spacing between successive horizontal rows of projecting portions of the spacer construction; illustratively, this spacing may be equal to the vertical spacing between the parts 98 and 104 of the structure of Figure 4 or the vertical spacing between alternate pairs of 50 arms of the spacer structure of Figure 2.

Furthermore, the configuration of the strips 55 143, 144 is such that the troughs therein occur at spacings equivalent to the spacings horizontally between the vertical rows of projecting parts of the structure of Figure 4 so that there is one 60 trough, for example, for each of the parts 98, 99, 100, etc., of Figure 4. Where the spacer of Figure 2 is employed, enough spacer members are employed and they are so spaced as to provide one spacer for each trough of the corrugated strips.

These corrugated strips are secured crosswise 65 of the sheet members 141, 142 in parallel to each other and vertically spaced by the vertical dimension of the projecting portions 98, 104, etc., 65 of Figure 4, or the vertical spacing of the alternate arms of the structure of Figure 2. These strips 143, 144 are secured to their respective sheet members 141, 142 in any suitable manner, illustratively by a suitable cement indicated in 70 Figures 33 and 34 at 145, the strips being apertured as at 143^a to permit the cement 145 to pass therethrough and into engagement with the sheet material, the latter being also preferably slotted or recessed as at 142^a and 141^a to let the cement 75

enter into the recesses and thus make a better bond with the sheet material. The cement 145 preferable also overlaps the upper and lower edges of the strip members thereby to be brought 5 into engagement with other portions of the sheet material.

Sheet members, such as members 141 and 142 of Figures 33 and 34, thus equipped with reentrant strips, illustratively the corrugated strips 143, 10 144, respectively, are interrelated with the spacer means, the projecting portions of the strips engaging between the vertically spaced projecting portions of the reinforcing spacer means (Figure 4 or Figure 2), this interrelation requiring no 15 relative sliding movement, and resulting in the interrelations shown in Figures 33 and 34.

If, thereafter, concrete or cement is poured in between the sheet members 141, 142, the concrete fills all of the spaces between each sheet member 20 and the sheet metal reinforcing member, between the latter and the re-entrant strips, etc., and thus a unique and dependable bonding action results for the concrete interengages and interlocks with the various parts and also bonds with the faces 25 of the sheet material itself.

In Figure 10 there is shown another of the various possible ways of assembling the sheet material to a reinforcing spacer construction of the kind shown in Figure 4. The latter in all of its 30 rib portions R₁ is provided with apertures 150 (Figures 10 and 4), thus forming horizontal and vertical rows of apertures. The sheet material shown at 151 and 152 in Figure 10 is provided with slots, as was described above in connection 35 with Figures 16 and 18, for example, for the reception of fastening devices 152 (see Figure 10) which may be made of wire or sheet metal strips suitably shaped, cut, or stamped to provide oppositely directed prongs or tongues 152^a and 152^b 40 (like the prongs 124^a and 124^b previously described) so that they may engage with the T-shaped slots in the sheet material or may be made to undercut ordinary slots in the sheet material while at their other ends the members 45 152 have one or more, illustratively two, yieldable or spring prongs 152^c and 152^d (Figure 10) shaped and directed as shown so as to be receivable through the apertures 150 when moved in one direction only. These prongs 152^c, 152^d form 50 a part like an arrow head with yieldable wings or sides which yield as the member 152 is forced into the aperture 150 whereupon they spring outwardly after the arrow head part has passed through the aperture. Thus, the sheet material 55 and the sheet metal core and reinforcing member are secured together for the reception of concrete or like plastic material.

This arrangement also facilitates assembly particularly on the job.

60 Recurring to the form of construction shown in Figures 33 and 34, I may, however, instead of securing strips like strips 143 and 144 to the sheet material secure thereto in parallel relation and appropriately spaced strip-like members 160, as shown in Figure 25, made of perforated sheet material or of wire mesh with the apertures approximating one-quarter of an inch in dimension, the members being preferably given a semi-circular cross-section and being provided 65 with tongues 160^a and 160^b running lengthwise thereof adapted to rest against the sheet material shown at 161 in Figure 25. A cement 162 secures the mesh-like material 160 to the sheet material, interlocking therewith by way of the 70 slots 161^a therein and interlocking also with the 75

member 160 by way of its apertures and cross-pieces. The member 160 thus also reinforces the sheet material.

Or the member 160 may be formed as shown in Figure 26 in which the lengthwise extending 5 tongues or flanges are bent inwardly as at 160^b and 160^c, the cement 162 interlocking with both member 160 and the sheet material 161, as was above described.

In application the members 160 of the sheet material are spaced as is better shown in Figure 35 to be received between the rows of arms or projecting portions of the spacers which may be of the type shown in Figure 2 but preferably are of the type shown in Figure 4; in the latter case 10 the members 160 extend crosswise of the sheet metal reinforcing core member of Figure 4, as shown in Figure 35, being received in the horizontal recesses between vertically displaced rows of projecting parts. Thereupon and at suitable 15 intervals I insert heavy wires or rods 163 and 164 (Figure 35) down through the loops formed by the projecting portions of the construction, such as the members 99, 105, etc., of Figure 4, and also pass these wires or rods through the 20 mesh or suitable apertures in the members 160, thereby securing a satisfactory assembly of the parts for the reception of the poured concrete 25 or cement.

I may, however, also secure to the sheet material but this time extending vertically and parallel to each a plurality of members, one of which is shown in Figures 23 and 24 at 170, the sheet material being indicated at 171. The member 170 is provided with a rib 170^a extending centrally 30 35 thereof and throughout its length, thus to give the member 170 adequate rigidity and permitting the use of thinner sheet metal.

It has portions 170^b and 170^c to each side of the central rib 170^a apertured as at 172 to permit 40 free access therethrough of the cement 173 and to interlock with the latter for securing the member 170 to the sheet material 171.

Extending lengthwise along the outer edges of the portions 170^b and 170^c are flanges 170^d and 45 170^e which, as shown in Figure 24, are thus held spaced away from the sheet material 171.

These flanges 170^d and 170^e are thus available for engagement in back of them of the flange portions 76 (see Figure 2) of the reinforcing 50 spacer construction there shown, the flanges 76, as is better shown in Figure 24, being appropriately bent to take in back of the flanges 170^d and 170^e. By this means two spaced sheet members may be quickly assembled to the spacers 60 55 of Figures 1 and 2, and thus prepared for the reception of the concrete or other plastic material.

In the preferred method of erecting a wall or the like embodying the reinforcing core or spacer members and the opposed sheet members, as above described, I prefer to follow the method and use the apparatus, such as is shown in Figures 36 and 39. In Figure 36 is shown a foundation or flooring 180, illustratively of concrete, and with respect to which a wall is to be erected. I provide a plurality of uprights 181 (Figures 65 36 and 39) preferably of structural steel so as to resist bending or warping and position them vertically but spaced horizontally, preferably utilizing a bottom channel 182 (Figure 36) in which 70 to rest their bottom ends and thereby align them. Extending horizontally of these uprights 181, 181, etc. and vertically spaced, is a plurality of supports or brackets 183 (Figure 36) preferably 75 of angle cross-section or they may be of short 75

lengths each individual to its own upright 181. These support a plurality of horizontal members 184, 185, 186 (Figure 36) of a length commensurate with the length or section of the wall to be erected and they are companion pieces to a bottom member 187 (Figure 36) which rests against the left-hand face of the bottom channel 182. Further to insure proper alignment of the members 181 I provide a top channel member 187 (Figures 36 and 39) into which the upper ends of the members extend. Suitable hinged braces 188 (Figures 36 and 39) extend from upper portions of the vertical members 81 down into a channel 189 and also braces 188^a from the lower portions of the members 81 to the channel 189, the latter being suitably anchored as at 190 to the floor, the part 190 having a vertical part seated in a pipe 190 embedded in the concrete floor and having a horizontal threaded part 191 passing through the webs of the channel 189 and passing through the lower end of the brace 188. By means of nuts 192, 193 the channel 190 and hence the braces 188 and braces 188^a may be adjusted so that the left-hand faces of the uprights 181 fall in the desired plane.

To the left of the horizontal member 187, 184, 185, 186, I position a mat 194 made of any suitable relatively rigid sheet material, such as wood, composition board, sheet metal, or the like, and it may be and preferably is in sections. To the left of that I erect a suitable series of sheet members S¹ and S² with the sheet metal spacers and reinforcing members indicated generally at X in Figure 36, assembled together in any of the manners above described in detail, the flooring, base, or foundation 180 having been previously provided (Figure 36) with a channel member 195 whose flanges extend upwardly and which has tongues 196 cut and bent out of the channel portions and embedded (pressed into the concrete while still plastic) in the concrete or otherwise secured to the foundation or flooring 180, details of this structure being later described.

To the left (Figures 36 and 39) of the sheet metal S² I provide another mat 197 held in place by horizontal members 200, 201, 202 and 203 held horizontally by members 204 constructed like the members 183 and supported by or secured to uprights 205 spaced and constructed similarly as are the uprights 181 above described (see also Figure 39).

The lower ends of the uprights 205 are received in a channel member 206 which is anchored as by a hook-shaped bar 207 buried in projecting portions 198 of the concrete 180 and provided with a thread and nut 208 where it passes through a flange in the channel 206, such anchorages being provided at suitably spaced points (see Figure 39) whereby the bottom channel 206 may be nicely alined with the channel 182 (Figure 36).

The upper ends of the uprights 205 extend into a channel 209 thereby nicely to aline them also.

At suitably spaced points in the upper channels 209 and 187 I provide adjustable tie means generally indicated in Figures 36 and 39 at 210, each preferably comprising an inverted U-shaped strap member of heavy metal hinged as at 211 to the channel member 187 so that it may be swung in counter-clockwise direction, as viewed in Figure 36, over the wall structure and over the channel 209, a thumb screw 212 being provided in the left-hand portion of the member 210 so as to adjust the channel 209 into parallelism and proper spacing with respect to the companion

channel member 187. In Figure 39, these parts are shown with respect to two wall portions at right angles to each other, the parts for each wall portion being the same as above described and identified by similar reference characters.

The uprights 181 having as above described been positioned so that their left-hand faces (as viewed in Figure 36) fall in a plane that is substantially truly vertical, adjusting hand screws 213 threaded into the uprights 181 and engaging the horizontal members 184, 185, 186, etc., are now manipulated so as to aline the left-hand faces of the latter in a true vertical plane and thereby accurately to determine and position the mat 196 (Figure 36), and against this mat the wall sections made up of the sheet members S¹, S² and core members X, as above described in detail, are then positioned.

By means of the hand screws 214 in the uprights 205, the left-hand mat 197 is appropriately adjusted by the resulting adjustment of the horizontal members 200, 202, 203, and thereby the outer sheet members S² are properly alined.

Furthermore, the sheet members S¹ and S² are thus dependably and rigidly supported in proper vertical and parallel positions and it will be noted that the arrangement is such that the sheet members S¹ and S² are prevented from separating from the intervening core or spacer and reinforcing means; thus, I am enabled with certainty to prevent any of the above described means for securing the sheet members and the reinforcing core or spacer structure from being subjected to severe strains as might result when the concrete is poured therebetween, particularly if it is tamped or otherwise forced into position. For that matter the means and method just described and as shown in Figures 36 and 39, make it possible, under some circumstances and where desirable, to dispense entirely with such securing means in which case the two opposed mats 194, 196 hold the sheet material and the interposed core or spacing means in appropriate assembled relation for the reception of the poured plastic material, preferably cement or concrete, and in such case the plastic material or cement bonds itself to the inner faces or surfaces of the sheet members S¹, S², the latter being preferably appropriately treated as by roughening the inner surfaces or slotting them, as is illustratively shown, for example, in Figures 16-19 and 21-23, the cement entering into the slots or recesses and securely bonding with the sheet material. In Figures 21-22 the sheet material 171 is shown as provided with slots or recesses 215 appropriately and preferably uniformly distributed throughout one face of the sheet member; it is that construction that is particularly advantageous where cement or the like is to unite with or bond with various of the different surface areas or the entire surface area thereof. Figures 23 and 24, already above described, show, for example, how these distributed recesses 215 become available where necessary when the sheet metal member 170 is cemented thereto.

Recurring to Figures 36 and 39, it is to be understood that though I have shown in Figure 39 reinforcing spacer members of the type of Figure 2 above described, it is to be understood, as already above mentioned, that, in so far as broader and other features of my invention are concerned, the core structure of Figure 4 may be employed, as is later described in connection with Figure 3. Where, however, the spacer

construction of Figure 2 is employed, particularly in the absence of any securing means and means for securing the sheet members S^1 and S^2 to the spacer members, I may and preferably do 5 employ horizontally extending spacer members, such as shown at 216 in Figure 40, for spacing the spacer members horizontally. These horizontal spacer members 216 are preferably made of sheet metal, rolled or formed to provide one or 10 more reinforcing ribs 217, the latter being given any suitable cross-section to improve the strength and rigidity of the member 216 and illustrative and possible cross-sections are shown at 217^a in Figure 41, at 217^b in Figure 42, and 15 at 217^c in Figure 43.

These horizontal spacer members 216, furthermore, are provided in their lower edge with slots 218, or rather and preferably with pairs of slots, the slots of each pair being spaced apart by a distance approximating the smallest spacing center to center of the arms of the spacer structure of Figure 2, so that the long spacer member 216 may be positioned in a horizontal plane to one side of the central ribbed portion 70 (see Figure 25 2) in the space between any two vertically spaced pairs of arms that extend to the same side of the ribbed portion 70 and thereupon, upon giving it a downward movement, the two arms of each vertical spacer 69 (Figures 2 and 40) riding into 30 and are received by the two slots of a pair, as is better shown in Figure 40.

By this arrangement and with suitably distributed pairs of slots 218, the vertical spacers 69 may be given any desired horizontal spacing and by using two or more horizontal spacer members 216 a reinforcing and spacer structure may be built up against, for example, the one mat 194, preferably with the sheet material S^1 interposed therebetween, and then the other 40 sheet material S^2 erected against the outer side of the reinforcing spacer structure in the manner above described and shown in Figures 36 and 39. Thus, the resultant wall is built up for the reception of the cement or concrete 45 which thus becomes strengthened and reinforced both vertically and horizontally, vertically by the spacers 69 and horizontally by the spacers 216 (Figure 40). In so building up the spacer structure, it is preferably based upon the above 50 described channel 195 (Figure 36) which, by the way, is better shown on an enlarged scale in Figure 40, from which also better appears one of the plurality of tongues 196 that are embedded into the cement or concrete flooring or 55 foundation 180.

If it is desired to utilize the sealed air cell structure 63 above described and shown in connection with Figure 1 or the building unit structure 60 of Figure 1, with its advantages and features as to heat insulation, etc., as described in my above-identified applications, a suitable number of such building units are built up and interposed between the pad 194 and the sheet member or members S^1 , and to illustrate this manner of assembly of the structure I have shown the same in Figure 3. Turning then to Figure 3 there will be seen the inner pad 194 and the outer pad 197, each supported and erected and adjusted in the manner described above in connection with Figures 36 and 39, the parts, however, being now given a greater spacing so as to accommodate adjacent the pad 194 the building units 60, each comprising an inner sheet member 61, an outer member 62, with interposed sealed 70 air structure 63, as described above in connection

with Figure 1, and it is in that manner, with the aid of the inner and outer pads 194, 197 that the earlier above described wall structure shown in Figure 1 may be erected and constructed, the spacer members 69 and the outer sheet member 66 of Figure 1 being assembled as was there described, the outer pad engaging and reinforcing the outer sheet member 66.

However, I may wish, as distinguished from the wall structure of Figure 1, to build up the composite wall by using building blocks or units, such as the unit 60 of Figure 1, and concrete or cement-receiving units or sections embodying sheet metal spacers, such as those of Figure 2 or Figure 4, with sheet members related to each side thereof, as was fully described above, utilizing where desired suitable means for securing the outer sheet members respectively to the two sides of the sheet metal core or reinforcing means. Thus, in Figure 3 I have shown to the left of the 20 wall portion that is made up of the building units 60, a cement or concrete-receiving structure made up of inner sheet members 220 and outer sheet members 221 with the above described sheet metal reinforcing and spacer means indicated in 25 Figure 3 at 222 and which may be that of Figure 4 though it will be understood that I may also employ that of Figure 2. In such case it is desirable to achieve a securing together, in any suitable manner, of the adjacent sheet material or 30 members 62 and 220 and illustratively I provide on the adjacent faces thereof suitably spaced dovetailed grooves 223 (see also Figures 19 and 20) which I may, furthermore, line with suitably shaped sheet metal members 224, as shown in 35 Figure 20, the latter lending themselves to molding into the material of the sheet member where the latter is made of a composition and thereby facilitating the manufacture thereof. In building up the wall structure of Figure 3, therefore, 40 the two adjacent sheet members or materials 62 and 220 are built up with these dovetailed grooves facing toward each other and aligned with respect to each other, as is shown in Figure 3 and is shown also fragmentarily but on a larger scale in Figure 12, and having thus aligned them I would insert into the two juxtaposed slots, 45 now forming a common or single recess 224, part of which is one sheet member and the other part is in the other sheet member, a key member or members 225 shaped as shown in cross-section in Figure 12, thus securely locking the two sheet members 62 and 220 together. The latter may be otherwise secured together, as by cementing; this may be achieved in the shop or on the job, as is true also of the securing of the sheet 50 metal core.

Thus, the cement or concrete may now be poured in between the sheet members S^1 and S^2 of Figures 36 and 39 or in between the corresponding sheet members indicated at 221 and 220 in Figure 3, with results already above described.

Recurring to Figures 36 and 39, where it is desired to form a support for floor beams, I lay in position, preferably after having poured the concrete into the structures of Figures 36 and 39, longitudinally extending members of structural steel cross-section, as indicated at 230 in Figures 36 and 38. Members 230 go all around the four walls of the room or building, at ceiling level, 65 being suitably interconnected at the corners, thus forming a tension and compression structure girdling the walls. Illustratively and preferably the member 230 is T-shaped when viewed from the left in these two figures and at the floor 70 75

- beam intervals, I cut the upper vertically extending web 231 at two spaced points and bend it into the plane of the horizontally extending web, as is indicated at 232 in Figures 36, 37 and 5 38, forming a broad-based platform or saddle upon upon which to rest the cross-beams 233, the latter being preferably structural steel I-beams (Figures 37 and 38). Screws or the like 234 secure members 230 and 233 together.
- 10 The members 230 rest upon the sheet metal core or spacer or reinforcing means and become embedded in the concrete, and since they extend throughout the length of the wall structure, the load of the floor beams 233 becomes thereby uniformly distributed to and throughout the reinforced concrete portion of the wall. The latter, due to the character of the core or reinforcing means, may be made of relatively small thickness and still more so where the inside wall thereof is 15 provided with suitable insulating means such as is shown in Figure 1 and described in connection with Figure 3. Furthermore, the manner of resting the floor beams 233 (Figures 37 and 38) onto the reinforced concrete portion of the wall structure makes it possible to employ a sealed air cell 20 structure (Figures 1 and 3) that need have lesser resistance to compression than would otherwise be the case.
- Having thus provided floor beams 233 (see Figure 37), the ceiling sheet units 235 may be secured in place and these are made of any one of the above-mentioned materials or the like and are preferably provided with slots 236 appropriately distributed preferably commensurately with 25 the spacing of the I-beams 233. They are rested against the lower flanges of the I-beams and then keys 237 made of any suitable material such as a 30 suitably heavy and strong wire bent up as shown in Figure 37 are used to hold them in place.
- 40 Each key 237 is provided with prongs 238 at its lower end, the upper end being similarly T-shaped and forming a handle. The oppositely directed prongs 238 are inserted in the slot 236 which may be T-shaped, as was described above in connection with Figure 17, or they may be ordinary slots; in the former case the prongs 238 take into the undercut portions of the T-shaped slots and in the latter case, where the material of the sheet members permits they act as cutting tools 45 to gouge out or undercut the slots and in cross-section virtually make them similarly T-shaped, all in the process of giving the members 237 a 90° turn. In either case, the upper T-shaped portions have one arm thereof swung over and onto the adjacent lower flange of the I-beam 233, thus holding the ceiling sheets 235 against falling down. As shown in Figure 38 I may and preferably do 50 employ suitable pins 239, driven into the ceiling sheets 235 one on each side of the upper T-shaped or supporting portion of the members 237 to prevent the latter from rotating and thus coming out of engagement with either the flange of the I-beam or the slot 236 of the sheet material 235.
- 65 These securing devices 237 may be made of any suitable metallic construction and where made of wire, as indicated in Figure 37, they are inexpensive and lend themselves to quantity production.
- 70 The flooring may then be laid in place and that also is preferably of a suitable sheet material of the type and kind already above mentioned and in Figure 37 a section thereof is shown at 240; it too is provided with T-shaped slots 241 suitably spaced and spaced commensurately with the spac-

ing of the I-beams 233. Into these T-shaped slots are received sheet metal members 250 having T-shaped base portions the opposite prongs or arms of which are indicated at 251 suitably dimensioned to be received in the bottoms of the T-shaped 5 slots, and each has a horizontally extending portion 252 that can take in under the upper flange of the I-beam 233.

The ceiling sheet units 235 and the flooring sheet units 240 are preferably of relatively large 10 size, such as four feet wide and ten or twelve feet long.

Inside or partition walls I preferably construct in the manner shown in Figures 27 and 28. Here again I preferably employ, for the two sides of the 15 wall, sheet members 260, 261 made of any of the materials earlier above mentioned, such as composition board, fiber-board, plaster-board, or the like, provide them with T-shaped slots 262, as shown in Figure 28, the slots being like those 20 above described in connection with Figures 16-18, and the sheet members 260, 261 I hold in spaced relation by spacers generally indicated at 263, running or extending the spacers preferably vertically. 25

The spacers 263 are preferably made of sheet metal and are, like the reinforcing spacer or core members earlier above described, provided with a central rib portion 264 (Figures 27 and 28) to stiffen and strengthen them against bending and 30 to each side of the central rib portion 264 I provide auxiliary ribbed portions 265 which I may, if desired and as shown in Figures 27 and 28, subdivide into appropriate relatively shorter lengths and alternating these shorter lengths as to the 35 direction in which the bulge or rib extends out of the plane of the sheet metal, all as is shown in the two figures.

The two vertically extending edges I provide with alternate pairs of prongs or tongues; thus, 40 there are tongues 266 bent in opposite directions to form a T-shaped end portion that is received in the T-shaped slot 262 of the sheet material and two tongues 267, formed by cutting or slitting the metal further back and bending the tongues 45 outwardly in opposite directions and to a greater extent than the tongues 266, as is better shown in Figure 28, the parts being so proportioned that, with the tongues or prongs 266 bottomed in the T-shaped slots 262 the larger and wider tongues 50 267 rest against and engage the inner face of the sheet material, thus insuring proper and parallel spacing of the sheet members 260, 261, and thus also insuring that the spacer members 263 do not take a diagonal position but extend at right angles 55 to the respective sheet members.

The partition wall construction is thus erected but within a bottom channel member 270, as shown in Figures 27 and 28, the parts being proportioned so that the partition wall structure is 60 snugly received within and between the upwardly directed webs or flanges 271 of the channel member 270.

At suitable points along the flanges 271, 272 I provide U-shaped slits to provide tongues or 65 tabs 273 which, as shown in Figures 27 and 28, can be bent or otherwise forced inwardly to take up any possible play between the partition wall structure and the channel member 270 and virtually to interlock therewith and hold it in assembled relation.

Out of the flanges 271, 272 of the channel 70 270 I also slit and bend tabs 274 apertured, as shown in Figures 27 and 28 for the reception of a fasten- 75

ing member 275, which may be a nail, screw, bolt, rivet, or the like, thus anchoring the channel 270 and hence the partition wall securely to the floor. Or, I may adopt a form of anchorage above described in connection with the channel members 195 of Figures 3 and 36.

The upper end of the thus built up partition wall structure is similarly received and telescoped within an upper channel member 276 provided with similarly formed tabs 277 by which it may be secured to the ceiling structure or to the ceiling beams and provided also with tongues or tabs 278 which may be forced or pressed inwardly to take up any play between the partition wall and the channel.

The upper channel member 276 preferably has the lower ends of its channels 270 and 280 provided with outwardly bent beads or flange portions 281 and 282 (Figure 27) to be received in a groove 283 (see now Figure 29) formed in a molding or coping member 284, thus to be supported by the bead 283, and having its upper end resting against the ceiling 285 and secured thereto by a suitable fastening member, such as a screw 286, thus concealing the structural steel parts and finishing the junction between the wall and the ceiling. In this connection, it is to be noted that the telescopic relation between the partition wall structure and the upper channel member 276 permits relative movement telescopically therebetween to compensate for changes in dimension due to temperature changes, for example, but it is to be noted that such changes do not affect the junctions between the coping or molding 284 and the ceiling and the partition wall, any sliding movement of the latter relative to the channel 276 being also relative to the lower end of the molding or coping 284.

In so far as certain features of my invention are concerned, I also make it possible, where desired, to avoid in the construction of a building sharp corners; for example, referring to Figure 39 it will be recalled that there are there shown two wall structures, in course of construction, extending at right angles to each other. The inside wall corner may be and preferably is a right-angle corner formed by the inside sheet members S^1 but if desired the outside corner may be formed by interposing in the corner formed by the two pads 197 a sheet member 290 made of any of the materials earlier above described, but appropriately curved throughout a suitable arc and alined along its edges with the edges of the sheet members S^2 and secured thereto by any suitable securing means, such as cement, or the like, as indicated at 291 in Figure 39, or by means later described. To strengthen and reinforce the concrete in this curved corner, a spacer member, such as that of Figure 2 may be interposed, as shown in Figure 39, it being noted that the spaced arms on one side of the spacer member permit the reception therebetween of the extreme corner junction of the inner sheet members S^1 .

Other means of joining the curved sheet section 290 to the sheet members S^2 are shown in Figure 50; in that construction the member 290 may be made thicker and provided with grooves or slots 290^a and 290^b along its vertical edges for the reception of tongues 291^a and 292^a of members 291 and 292, respectively, formed integrally with or secured to the sheet members S^2 , the arrangement dependably interlocking and holding the curved member 290.

Or I may and preferably do form the curved member, as is indicated at 293 in Figure 51, in

which a portion E thereof is of an arcuate extent of 90° and has portions F and G extending along straight or uncurved edges, thereby to form nicely of interfitting with and extension of the sheet members S^2 and S^2 .

5

To the curved member 293 (Figure 51) I may secure sheet metal straps 294 at suitably vertically spaced intervals, securing them as by cement 295 or other suitable means, these straps 294 extending beyond the edges of the member 293. At 10 their ends the members are flanged as at 296 and 297 where they are slit and bent to provide oppositely directed prongs or tongues 298 and 299 to be received in T-shaped slots formed along the inner faces of the sheets S^2 and S^2 , for interlocking engagement therewith in the manner already above described. These junctions, furthermore, may be anchored or set by cement, as indicated at 300 in Figure 51.

15

In Figure 11 I have shown how with my construction I can provide curved edges of both inside and outside walls. Thus, in Figure 11, will be seen the outside sheet members S^2 and the inside sheet members S^1 with suitable reinforcing core or spacer means X therebetween, illustratively as above described in connection with Figures 3, 36 and 39, the sealed air cell structure 63 with the inner sheet material 61 and the outer sheet material 62, the latter being joined to the sheet material S^1 by key members 225, as above described. At the left-hand portion of this wall there is to be a door 305 and at the right-hand end a windowframe 306. To the right-hand edge of the inner sheet member 61 there is alined one edge of a curved sheet section 307 of 90° arc, secured to the inner sheet member 61 and to the window-frame 306 in any suitable manner, preferably to the latter by a suitable cement, or the like, its edge being received between appropriate beading 308 and 309 of the windowframe or door jamb, preferably of steel.

20

To the left-hand vertical edge of the inner sheet material 61 there is secured and alined a curved sheet section 310 having a 90° arc portion 310^a and a straight portion 310^b which abuts with its inner side face against the left-hand edges of the sheets 62 and S^1 , extending somewhat beyond the latter to receive a sheet metal strip 311 shaped as shown in Figure 11, providing a seat for the edge of the portion 310^b and a seat or recess for the reception of a curved sheet section 312 shaped like the member 293 above described in connection with Figure 51. The right-hand portion of the latter is alined with and secured to the outer sheet member S^2 by a sheet metal strap member 313 provided with T-shaped prongs 314 and 315 for reception in T-shaped slots appropriately positioned in the members 312 and S^2 , a suitable cement 316 anchoring the parts in place.

25

The member 311 thus secures the parts together in such a way as to provide a seat for the inwardly swinging door 305. The concrete that is poured in between the sheet material S^1 and S^2 completes the anchorage of all of the parts.

30

At the right-hand vertical edge of the sheet material S^2 in Figure 11, there is provided a curved member 317 like the member 312, its one edge seated between beading 318 and 319 in the window frame and its left-hand edge secured to the sheet material S^2 by a sheet metal strap member 313 and related features similar to those described as connecting the parts 312 and S^2 .

35

These curved sheet sections, such as the sec-

75

- tion 293 of Figure 51, I make up out of corrugated sheet material generally indicated in Figure 48 at 320 in which it will be seen that there is an arcuate portion E of 90° extent followed by two straight or plane portions F and G one at each end of the portion E. The next corrugation or wave portion is similarly made up of a straight portion F, a portion E of 90° extent, and portion G that is straight or plane.
10. This sheet material 320 may be fabricated of any suitable composition or plastic material, illustrations of which are given above, and preferably its face H being the upper face as viewed in Figure 48, is given any suitable surface finish.
15. Accordingly, if this corrugated sheet material is cut along lines 321, 322, a curved sheet section of 90° extent results. If, however, it is cut along the lines 323 and 322, a sheet results that has a 90° curved portion E and a straight portion F; 20 if the latter portion F is desired to be of greater extent, the cutting is along lines 324 and 322, resulting in a sheet that comprises a 90° curved section E and a plane section F and G. On the other hand, the cutting may be along lines 323 25 and 324, resulting in a section like the section 293 of Figure 51, or the cutting may be along the lines 324 and 326. Thus, I am enabled to provide curved sections to suit the varying needs, some of which are illustrated in Figure 11.
30. With one face H finished, cutting along the lines above indicated gives a finish surface on the convex surface, thus suiting the needs for a finished exterior surface, as indicated in Figure 11. Where, however, it is desired to provide a 35 curved sheet section with its concave face finished, the cutting may be along combinations of the lines 322, 325, 326, 327, 328 and 329 of Figure 48, giving like combinations of sheet sections, as above described, but now with the concave face 40 finished; such latter elements may be employed in making a coping such as shown in Figure 29 where a plain curved or concave coping is desired, or, for example, where an inside corner is desired to be rounded.
45. In Figure 49 is shown in elevation a portion of a window or doorframe, such as those described above in connection with Figure 11, giving the appearance and interfitting of the vertical or side curved sheet sections 330 and 331 and the upper 50 horizontal curved sheet section 332.
- Recurring to the core structure shown in Figure 4 and above fully described, it will be understood that it may be made in any suitable dimensions. The thickness when viewed in plan may be 55 varied to be commensurate with the thickness of the concrete veneer or concrete wall sections desired while the length and breadth of the core structure may match the size of the building units employed as already indicated above or that 60 may be fabricated in dimensions commensurate with those of the ultimate wall itself. Thus, the vertical height may be on the order of ten or eleven or twelve feet corresponding to the usual ceiling height, if desired.
65. Where core sections are arranged side by side and in abutting relation, it is desirable to secure them together where they join or abut and in Figures 4 and 5 I have shown the manner in which such junction may be effected. Thus, referring first to Figure 5, the left-hand vertical end or edge of the reinforcing and spacer or core construction will be seen to terminate in wing-like parts 70 W², W², W², etc., bent or shaped in opposite directions, while the right-hand end or vertical edge 75

terminates in oppositely bent wing portions W¹, W¹, W¹, etc. In plan these wings appear as shown in Figure 5 and all of them are again bent inwardly to give them a hook-shape, as indicated at H¹, H¹ in Figures 4 and 5. These hook-shaped parts are brought into abutting relation, as shown in Figure 5, and then a split or slotted tube-like sheet metal member 350 is passed vertically down along the inside of the aligned wings W¹, W¹, thereby dependably interhooking with the hook-shaped parts H¹, H¹ and in effect keying them and the core sections together. Preferably, the sheet metal key member 350 is made of relatively heavy sheet metal and it may, if desired, be given an appropriate resiliency in order thus always to grip the hook-shaped parts together.

Where, as above described in connection with Figures 5 and 6, I employ an outer sheet metal material, such as copper, chromium, aluminum, or the like, as is indicated at 111 in Figures 5 and 6, I preferably join the sheets of the latter along vertical seams by shaping the adjacent edges thereof into hooks 111^a and 111^b, but I preferably make the latter of relatively large radius so that they may receive therein the hook-shaped parts H¹ and H¹ of the vertically aligned wings W¹ and W² of the two adjacent core sections. I then provide a sheet metal slotted tube-like member 351, hook-shaped as shown, and pass it vertically down so as to interhook with the hooks H¹ and H¹ at the same time and by reason of the construction just described, interhooking also with the hooks 111^a and 111^b of the two metal sheets 111, 111.

Thereby a dependable and easily assembled 35 mechanical interconnection is achieved.

In either case where the member 350 or 351 is employed (Figure 5) the subsequent pouring and setting of the concrete makes the interlocking and interengagement of these parts with the hook-shaped portions permanent.

Where it is desired to connect together reinforcing spacer structures like that of Figures 1 and 2, I may employ a similar construction, particularly where the outer sheet material is sheet metal, and in Figure 52 I have shown several of these reinforcing and spacer constructions, at 355, having their arms 356, corresponding, for example, to the arms 76 of Figure 2, hook-shaped as at 357, to receive a slit tube-like connector member 358 that interhooks with the hooks 357 of a number or all of the arms 76, 76 of the two adjacent reinforcing members 355 that are thus to be connected together.

The outer sheet material may be sheet metal, as indicated at 360, and at its vertical edge it is hook-shaped, as at 361, to have nested therein the hook 357 of the adjacent arm 356, thus forming a composite hook to receive a slit connecting sleeve or tube member 362 to connect these parts to the adjacent parts, as will presently be done. The arms 363 of the spaced member 355 may be provided with oppositely bent prongs 364, as was above described in connection with Figures 11 and 30, to be received in T-shaped grooves or slots in the inside sheet member 365 which may be of any desired or suitable material, preferably non-metallic, as already above described.

Still referring to Figure 52 I have shown at 370 a curved sheet member to make exteriorly 70 a rounded surface for the corner of the building and at its right-hand end it is hook-shaped, as at 371, being thereby engaged by the above described connector sleeve member 362 and being thereby accurately alined with the sheet metal 75

member 360 and also dependably and securely connected therewith.

At its other end the sheet metal curved corner member 370 is also hook-shaped, as at 372, the latter, like part 371, extending throughout its length so that it may be engaged by connector sleeve members 373, like the member 362 above described, member 373 also interengaging with the hook-shaped end 374 of the adjacent sheet metal member 375 which is held spaced from the inside sheet member 376 by spacers which may be arranged and constructed like the spacers 355 above described but which, for purposes of better illustration, are shown in Figure 15 52 to be in the form like that shown in Figures 4 and 5, one of the wings W^1 of which is hook-shaped and nested in the hook-shaped part 378 and is engaged also by the connector tube-like member 373, thus illustrating how the core structure of Figure 4 may be interrelated and interconnected with a curved exterior corner sheet metal part 370.

When the space between the outside and inside sheet members of Figure 52 is filled with concrete the vertically and lengthwise extending connector tubes or sleeves 373 and 362 become permanently anchored against movement or against unbending and thus a solid and dependable anchorage of the outer sheet metal facing is achieved.

However, and preferably, I provide a reinforcing core structure, preferably of sheet metal, for the corner construction of Figure 52 and for interconnection with the core structures of the two right-angled walls, that corner core structure serving also to facilitate the mounting of the curved sheet metal outer member 370 of Figure 52. In Figure 53 I have shown in perspective a fragmentary portion of such a corner core structure.

Accordingly, referring to Figure 53, the core structure generally indicated by the reference character 380, is preferably cut, shaped, pressed or punched, or otherwise formed, out of sheet metal so as to provide side portions 381, 382, that extend vertically, throughout the length of the core 380, and at the respective sides or vertical ends thereof. These side portions 381, 382 may be stiffened or strengthened as by ribs 383, 384, respectively, in a manner analogous to the ribs R of the core structure of Figure 4 or the ribs 11 of the spacer structure of Figure 2. They are thus given substantial load-bearing capacity and substantial strength and rigidity and resistance against bending, while maintaining lightness of weight and inexpensiveness of construction.

Intervening the side portions 381, 382, and in the process of making the core structure 380, the sheet metal is slit or cut in parallel horizontal but vertically spaced lines and the resultant cross-bands, bridging between the side parts 381, 383, are alternately pressed and shaped in opposite directions out of the plane of the initial sheet metal. Thus, the uppermost band 385 is pressed away from the observer, viewing Figure 53, and is the desired arcuate or curved shape, in the illustrative embodiment of Figure 52, that being a curvature along a 90° arc. The curved band part 385 may be and preferably is corrugated or ribbed, as at 386, 387.

The next band part, in a downward direction, is forced in the opposite direction, now toward the observer viewing Figure 53, to give the part

389, which comprises two portions 389^a and 389^b at right angles to each other.

The next lowermost band 390 is pressed outwardly and shaped like the part 385, the next one down is bent toward the observer to give the right-angled part 390, and so on down for as great a length as is desired.

The corrugations or vertical ribs 386, 387 not only strengthen the curved band portions but also serve as a means for compensating for the shorter linear length of the arc of curvature thereof, as compared to the linear length of the inwardly bent parts 389, 391, etc. Also, and in the process of formation, the vertically ribbed vertical side parts 381, 382 are bent or so shaped (as shown in Figures 52 and 53) that their planes will be truly at right angles to each other where the two walls (see Figure 52) are at right angles to each other, or at such angle as is required by the construction.

Furthermore, these side portions 381, 382 are flanged or hook-shaped throughout their length as at 393 and 394, commensurately with the hook-shaped parts of the sheet metal spacers or core structures, as above described.

Accordingly, referring now to Figure 52, the hook-shaped parts 393 and 394 of the corner core 380 are seated within the hook-shaped parts 372 and 371, respectively, of the outside curved corner sheet 370, and in any event are available for interengagement with the slotted sleeve-like connectors 373 and 362, respectively, for interconnecting the corner core 380 with the respective adjacent spacers or cores of the two side walls.

The subsequent pouring of the concrete fills all of the interstices or spaces provided by the corner core 380 and upon setting is dependably interlocked with the core, the latter reinforces the former, increases its load-carrying capacity, and achieves other numerous advantages.

Thus, it will be seen that there has been provided in this invention a building construction in which the various objects above noted, together with many thoroughly practical advantages, are successfully achieved.

As many possible embodiments may be made of the above invention and as many changes might be made in the embodiment above set forth, it is to be understood that all matter hereinbefore set forth, or shown in the accompanying drawings, is to be interpreted as illustrative and not in a limiting sense.

I claim:—

1. In building construction, in combination, a wall of a building comprising two spaced sheet members, reinforcing spacer means interposed between said sheet members, said means being made of sheet metal having portions thereof pressed alternately but always about substantially parallel axes out of the plane of the sheet metal and to either side of said plane, whereby said portions determine the spacing between said sheet members and the space between said members being obstructed, in the directions of said substantially parallel axes, substantially only by the cross-sectional thicknesses of the sheet metal of said spacer means to permit said space to be filled with a pourable material by pouring it in the direction of said axes, and means forming a connection between at least one of said sheet members and the portion of said sheet metal means engaging therewith.

2. A construction as claimed in claim 1 in which said connection-forming means comprises parts of said sheet member and of said portions

constructed to interengage upon relative movement therebetween.

3. A construction as claimed in claim 1 in which said reinforcing spacer means comprises a substantially central part that is ribbed along its length.

4. A construction as claimed in claim 1 in which said portions of said reinforcing spacer means are in the form of wing- or arm-like members carrying at their outer ends the part or parts that interengage with the part of said sheet member.

5. A construction as claimed in claim 1 in which one of said parts is prong- or hook-shaped and in which the other of said parts is recessed or cut to receive said hook- or prong-shaped part.

6. A construction as claimed in claim 1 in which said reinforcing spacer means comprises a plurality of sheet metal members together with means extending transversely thereof and receivable in the space between said portions.

7. A construction as claimed in claim 1 in which said reinforcing spacer means comprises a plurality of sheet metal members together with means extending transversely thereof and receivable in the space between said portions, said transversely extending means and certain of said portions being shaped to interengage.

8. A construction as claimed in claim 1 in which said reinforcing spacer means comprises a plurality of sheet metal members together with means extending transversely thereof and receivable in the space between said portions, said transversely extending means comprising a sheet metal reinforcing member having a plurality of slots or recesses into selected ones of which said portions are received, whereby the spacing of said plurality of reinforcing spacer members may be adjusted at will.

40 9. A construction as claimed in claim 1 in which there are a plurality of said reinforcing means arranged in edge to edge relation, and means for connecting together adjacent edges thereof.

45 10. A construction as claimed in claim 1 in which there are a plurality of said reinforcing means arranged in edge to edge relation, adjacent edge portions being substantially hook-shaped, and connecting means interengaging with said 50 hook-shaped edge portions.

11. A construction as claimed in claim 1 in which there are a plurality of said reinforcing means arranged in edge to edge relation, adjacent edge portions being flanged, and a longitudinally 55 slit sleeve-like member for interconnecting them said flanged portions being received within said slit.

12. A construction as claimed in claim 1 in which there are a plurality of said reinforcing means arranged in edge to edge relation, adjacent edge portions being flanged, one of said sheet members having an inwardly directed flange receivable between said flange portions, and means 60 securing said flange and flange portions together.

65 13. A construction as claimed in claim 1 in which the space between the two spaced sheet members and about said reinforcing spacer means is filled with concrete or the like, said concrete holding said connection means against disconnection.

70 14. In building construction, in combination, a wall having an inside finishing surface with means forming heat insulation on the outer side 75 thereof, said insulation-forming means having

secured thereto, on the outer side thereof, sheet metal reinforcing means, sheet material held in spaced relation by said reinforcing means, the space between said sheet material and said heat insulation-forming means being filled with concrete in which said reinforcing means is also embedded.

5 15. In a method of wall construction for a building or the like, the steps which comprise erecting a temporary mat structure and alining it in the desired plane, building up against said mat structure wall-surfacing means in the form of sheet members and interposing between the latter metallic reinforcing and core means, alining a second mat structure relative to the first and to the 10 overall spacing of said sheet members and reinforcing means and filling the space between said wall-surfacing means with concrete or the like, whereby said mat structures take up the thrust of 15 the concrete and prevent change in the said 20 spacing between said sheet members.

16. In a method of wall construction for a building or the like, the steps which comprise erecting a temporary mat structure and alining it 25 in the desired plane, building up against said mat structure wall-surfacing means in the form of sheet members and interposing between the latter spacing means to determine the spacing between said sheet members, erecting another mat structure in substantial parallelism to said first mat structure, adjusting one of said mats relative to the other so that said sheet members are spaced apart by the distance determined by said spacing means, and filling the space between said sheet 30 members with concrete.

35 17. In a method of wall construction for a building or the like, the steps which comprise erecting a temporary mat structure and alining it in the desired plane, building up against said mat structure a wall construction by placing building 40 units having heat insulation means faced by sheet material, the latter being face to face with and against said mat structure, erecting a second mat structure in substantial parallelism to said first structure but spaced from said building units, and filling the space between said heat insulation means and said second mat structure with means comprising sheet members rested against said second mat structure and concrete between said sheet 45 members and said heat insulation means.

50 18. In building construction, in combination, a wall of a building comprising two spaced relatively thin sheet members, reinforcing spacer means interposed therebetween, said means being of an expanse commensurate with the length and breadth of said sheet members and being made of sheet metal having interconnected portions thereof pressed alternately out of the plane of the sheet metal and to either side thereof and toward either of said sheet members and having said portions abutting said two sheet members respectively, at least one of said sheet members having means interfitting with said spacer means and at least one of said sheet members forming a wall face.

55 19. In building construction, in combination, a wall of a building comprising two spaced relatively thin sheet members, reinforcing spacer means interposed therebetween, said means being of an expanse commensurate with the length and breadth of said sheet members and being made of sheet metal having certain portions thereof extending in a plane for engagement with one 60 of said sheet members and other portions thereof 65 70

pressed out of the plane of the sheet metal and toward the other sheet member, still other portions of said sheet metal forming rigid interconnections with said first- and second-mentioned portions for holding them in their respective planes for engagement with said sheet members, at least one of said sheet members and said reinforcing means having means interengaging one another upon relative movement, during assembly, between said sheet member and said reinforcing means.

20. In building construction, in combination, a wall of a building comprising a plurality of building units each comprising spaced sheet members with interposed means forming a plurality of sealed air cells, said parts of said building units being shaped along their edges to interfit and adjacent units being by their said edges interengaged and interfitted in horizontal or vertical courses as desired, and thereby alining said sheet members, and a concrete veneer extending over the sheet members of a plurality of said interfitted building units at least on one side of the latter.

21. A construction as claimed in claim 20 in which said concrete veneer comprises reinforcing means extending along the alined sheet members on said side of said interfitted building units and embedded in the concrete.

22. A construction as claimed in claim 20 in which said concrete veneer comprises reinforcing means extending along the alined sheet members on said side of said interfitted building units and embedded in the concrete, the outer face of said concrete veneer being formed by suitable sheet material together with means forming a mechanical connection between said reinforcing means and at least one of said sheet means bounding said concrete veneer.

23. In building construction, in combination, a wall comprising a wall portion of sheet material presenting a substantially plane inner face and a second wall portion, said second wall portion comprising metallic core means having portions extending toward said plane face of said first portion and having other portions extending therefrom and adapted to be embedded in concrete or the like, said first-mentioned wall portion and said first-mentioned portions of said core means having means for relatively quickly attaching said core means to said first wall portion.

24. A construction as claimed in claim 23 in which said means for attaching said core means to said first wall portion comprises two means, one related to said first wall portion and the other related to said core means, and capable of interconnection upon relative movement therebetween.

25. A construction as claimed in claim 23 in which said means for attaching said core means to said first wall portion comprises two parts, one related to said first wall portion and the other related to said core means, one of said parts being in the form of an undercut recess and the other part having means seated in said undercut recess.

26. A construction as claimed in claim 23 in which said means for attaching said core means to said first wall portion comprises a plurality of pairs of interengageable parts capable of interengagement upon relative movement therebetween, one member of each pair being substantially uniformly distributed throughout and related to said face of said first wall portion and the other member thereof being substantially correspondingly uniformly distributed throughout said core means.

27. A construction as claimed in claim 23 in

which said core means is sectionalized into a plurality of sections, with means for readily securing said sections together in end to end relation.

28. A construction as claimed in claim 23 in which said core means is sectionalized into a plurality of sections, and telescopic means for securing together adjacent ends of said sections.

29. A construction as claimed in claim 23 in which said core means is sectionalized into a plurality of sections, adjacent ends of said sections being flanged, and means for readily securing adjacent flanges together.

30. A construction as claimed in claim 23 in which said core means is sectionalized into a plurality of sections, adjacent ends of said sections being substantially hook-shaped, and means interengaging adjacent hook-shaped flanges for securing said adjacent ends together.

31. A wall construction comprising, in combination, a fixed channel member positioned at the longitudinal terminus of a wall, two spaced and substantially parallel sheet members spaced apart by a distance commensurate with the inside spacing between the side walls of said channel, and spacer means interposed between said two sheet members for fixing said spacing therebetween, the unit formed by said sheet members and said spacer means being received at an end thereof within said channel member to form therewith a telescopic connection, together with means for substantially wedging said end between the side walls of said channel.

32. A wall construction as claimed in claim 31 in which said channel member is of sheet metal and has portions of at least one flange thereof pressed inwardly against the sheet member adjacent thereto.

33. In building construction, in combination, a wall comprising two spaced relatively thin sheet-like means and sheet metal means provided with a plurality of substantially parallel spaced ribbed members from which extend to both sides of the plane thereof a plurality of substantially uniformly distributed and alined sheet metal securing portions for engaging, and holding assembled to said sheet metal means, said sheet-like means.

34. In building construction, a wall comprising, in combination, a sheet metal core means comprising sheet metal having portions thereof pressed out of the plane of the sheet metal and at least to one side of said plane and into a plane displaced from said first-mentioned plane, said sheet metal having a part of greater length than any of said portions and being flanged or ribbed to resist bending of said core means in a direction transversely of said plane, sheet-like means alined with said pressed portions, said ribbed part holding said portions in alinement with said sheet-like means, and means mechanically securing the latter to said core means.

35. In building construction, a wall comprising, in combination, core means comprising a sheet metal member having portions thereof pressed alternately out of its plane and to either side of said plane and in substantially uniform distribution, thereby forming vertical and horizontal rows, on each side of said plane, of outwardly pressed portions, and sheet-like means resting against certain of said portions, there being strip-like parts of said sheet metal intervening certain of said rows and which parts are reinforced to resist bending transversely of their length to maintain said certain portions alined with said sheet-like means.

36. In building construction, a wall comprising, in combination, core means comprising a sheet metal member having portions thereof pressed alternately out of its plane and to either side of said plane and in substantially uniform distribution, thereby forming vertical and horizontal rows, on each side of said plane, of outwardly pressed portions, and sheet-like means resting against certain of said portions, certain of said rows being spaced to provide therebetween strip-like portions of said sheet metal which are ribbed lengthwise to resist bending thereof to maintain said certain portions aligned with said sheet-like means.
37. In building construction, in combination, a wall having three portions two of which make an angle to each other and the third being the corner portion interposed between the two, sheet metal core means for each of said two wall portions, said core means having parts thereof pressed alternately out of the plane of the sheet metal and to either side of said plane, and core means for said corner wall portion comprising sheet metal having parts pressed inwardly to substantially mate with the angle between said two wall portions and other parts pressed outwardly and shaped to approximate the desired external contour of said corner wall portion.
38. In building construction, in combination, a wall having three portions two of which make an angle to each other and the third being the corner portion interposed between the two, sheet metal core means for each of said two wall portions, said core means having parts thereof pressed alternately out of the plane of the sheet metal and to either side of said plane, and core means for said corner wall portion comprising sheet metal having parts pressed inwardly, each part being bent at an angle substantially similar to the angle between said two wall portions, and other parts pressed outwardly and shaped to approximate the desired external contour of said corner portion.
39. A wall construction as claimed in claim 37 in which said three core means have contiguous edge portions substantially aligned, said edge portions being provided with means for securing contiguous edge portions together.
40. A wall construction as claimed in claim 37 in which said three core means have contiguous edge portions substantially aligned, said edge portions being provided with means comprising flanges and readily attachable means for securing contiguous flanges together.
41. A wall construction as claimed in claim 37 in which said three core means have contiguous edge portions substantially aligned, said edge portions being provided with means comprising hook-shaped flange means interengaged for securing contiguous edges together.
42. A wall construction as claimed in claim 37 in which said three core means have contiguous edge portions substantially aligned, said edge portions being provided with means comprising hook-shaped flanges and longitudinally slit sleeve-like means for interconnecting adjacent hook-shaped flanges.
43. In building construction, in combination, a corner wall portion having core means made up of a strip of sheet metal transversely slit at intervals along its length to provide a plurality of strap-like parts, certain of said parts being pressed inwardly and bent to form an angle substantially similar to the angle of the corner and others of said parts being bent outwardly to approximate the desired external contour of said corner wall portion.
44. In building construction, in combination, a corner wall portion having core means made up of a strip of sheet metal transversely slit at intervals along its length to provide a plurality of strap-like parts, certain of said parts being pressed inwardly and bent to be accommodated within the thickness of said corner wall portion and others of said parts being pressed outwardly to approximate the desired external contour of said corner wall portion.
45. In building construction, in combination, a corner wall portion having core means made up of a strip of sheet metal transversely slit at intervals along its length to provide a plurality of strap-like parts, certain of said parts being pressed inwardly and bent to be accommodated within the thickness of said corner wall portion and others of said parts being pressed outwardly to approximate the desired external contour of said corner wall portion; the longitudinal marginal portions making an angle to each other equal to the angle of the corner, said outwardly bent parts merging into said marginal portions.
46. In building construction, in combination, a corner wall portion having core means made up of a strip of sheet metal transversely slit at intervals along its length to provide a plurality of strap-like parts, certain of said parts being pressed inwardly and bent to be accommodated within the thickness of said corner wall portion and others of said parts being pressed outwardly to approximate the desired external contour of said corner wall portion; the longitudinal marginal portions of said sheet metal being ribbed lengthwise.
47. In building construction, in combination, a corner wall portion having core means made up of a strip of sheet metal transversely slit at intervals along its length to provide a plurality of strap-like parts, certain of said parts being pressed inwardly and bent to be accommodated within the thickness of said corner wall portion and others of said parts being pressed outwardly to approximate the desired external contour of said corner wall portion, at least one of the longitudinal marginal portions of said sheet metal being bent lengthwise to provide a securing flange therefor.
48. In building construction, in combination, a wall comprising a plurality of sheet members having adjacent edges hook-shaped, core means comprising a plurality of sections having two adjacent edges hook-shaped, the said two hook-shaped edges being respectively seated within the two hook-shaped edges of said sheet members, thereby to form two adjacent composite hook-shaped parts, and means engaging said two hook-shaped parts to hold them against separation.
49. In building construction, in combination, a wall comprising a plurality of sheet members having adjacent edges hook-shaped, core means comprising a plurality of sections having two adjacent edges hook-shaped, the said two hook-shaped edges being respectively seated within the two hook-shaped edges of said sheet members, thereby to form two adjacent composite hook-shaped parts, and a longitudinally slit sleeve-like member over both of said hook-shaped parts for holding them against separation.
50. In building construction, a wall comprising a prefabricated relatively thin sheet-like member whose one side forms one face of the wall and whose other side is directly covered by

- sealed air cell means forming heat insulation, and a metal-reinforced concrete veneer extending along the outer face of said sealed air cell means and connected thereto.
5. 51. In building construction, a wall comprising a plurality of individual wall units each unit comprising a prefabricated relatively thin sheet-like material whose one side is adapted to form part of one face of the wall and having in abutting relationship to the other side thereof heat-insulating means, said plurality of units being related edge to edge so that one face of the wall is made up of the aligned first-mentioned sides of said sheet members, and means forming the other 10 face of the wall and comprising a built-up wall veneer coextensive with all of said units and extending over and against said heat-insulating means.
52. A wall construction as claimed in claim 51 15 in which said built-up wall veneer comprises a network of metallic reinforcing means coextensive with all of said units and interengaged with
- said heat-insulating means and a plastic material like concrete embedding said reinforcing means.
53. In building construction, a wall comprising two spaced prefabricated sheet members having interposed therebetween reinforcing spacer means comprising means made of sheet material having two sets of portions extending each to one side of the central plane of the spacing between said two sheet members and into respective engagement with the latter, the portions of each set being aligned in a plane and said two sets thereby presenting to their respective sheet members a plurality of aligned places of engagement, whereby said two sheet members are uniformly 20 spaced, at least one of said sheet members being provided with means distributed commensurately with the distribution of the plurality of portions of the one set engaging it for interconnection with said engaging portions.
